UNITED STATES PATENT OFFICE.

GEORGE E. O'NEILL, OF BROOKLYN, NEW YORK, ASSIGNOR OF ONE-HALF
TO JOHN T. WILLOUGHBY, OF BROOKLYN, NEW YORK.

APPARATUS FOR PITCHING KEGS OR BARRELS.

No 853,516.

Specification of Letters Patent.

Patented May 14, 1907.

Application filed December 17, 1904. Serial No. 287,802.

To all whom it may concern:

Be it known that I, GEORGE E. O'NEILL, residing in the borough of Brooklyn, county of Kings, and State of New York, have invented certain new and useful Improvements in Apparatus for Pitching Kegs or Barrels, of which the following is a full, clear, and exact description.

In order to simplify this specification I shall refer throughout to the barrels as kegs. It will be understood, however, that either kegs or barrels can be operated upon.

In the accompanying drawing I have shown crudely, but with sufficient clearness to enable one skilled in the art to make the same, a machine constituting one embodiment of my invention.

In this drawing, Figure 1 is a plan view of the machine, and Fig. 2 is a sectional elevation thereof.

In the drawing, *a* indicates a suitable pillar sitting in a pitch vat *b*. Supported upon ball bearings, or otherwise suitably supported by the pillar *a*, is a rotary table *d*. This rotary table is shown as provided with a down-turned edge *e*, in which edge gear teeth *f* (see Fig. 1) are cut, with which gear teeth a suitable pinion *g* gears, in order that, by rotating the pinion, a movement of rotation may be imparted to the table.

Mounted upon the table are a series of cradles or keg supports *h*. These cradles or keg supports are adapted to support kegs *i*. Immediately below the cradles *h* are pitch boxes *j*, provided with suitable nozzles *k*, and communicating with the pitch vats *b* by a port *l* closed by a swinging check valve *m*.

Pipes *o* communicating with the pitch boxes *j* serve to bring air pressure to the pitch boxes. These pipes extend into the hub of the traveling table, and are adapted to come one at a time opposite the delivery end *p* of the air pipe *q*. This air pipe *q* is provided with a controlling valve *r* provided with a handle *s* for controlling the air pressure.

It will be understood that the pitch is kept in a heated condition either by fire below the pitch pot or vat, or steam coils *t*, and that the air pressure serves to drive the pitch into the keg. The air pressure, of course, will be applied when each pipe *o* comes opposite the delivery end *p* of the air pressure pipe. It might happen, however, that when the parts

have reached this position there is no keg on the particular cradle which is in the active position. If some means were not provided whereby the apparatus will be prevented from operating, boiling pitch would be scattered around the room. In order to obviate this difficulty I provide a safety device which at the same time also serves as an operating device.

The safety device may be described as follows:—Upon a bracket or stanchion *u* is pivoted the end of a lever *v* carrying a heavy roller *w*, which is adapted to bear upon a keg, as shown, the free end of the lever *v* being pivoted at *x* to a link *y* pivoted at *z* to the operating arm *s* of the valve *r* for controlling the air pressure.

In order to relieve the air pressure, so that the pitch boxes may be kept full, I provide a cut away portion *l* in the standard of the pillar *a*. The operation of the machine and the method of pitching kegs will now be described in detail: The kegs are preliminarily prepared for pitching. This is done by subjecting them to the action of superheated steam at a pressure of about 150 pounds for several seconds. The superheated steam is at a sufficiently high temperature to soften and melt the pitch, which, therefore, runs out of the bung hole, being carried out by the steam.

The detail operation of the machine is as follows:—The kegs are placed upon the cradles with the nozzles inserted into their bung holes. The table is given a motion of rotation and as air pipe *o* comes opposite the pipe *p* air pressure forces the liquid pitch upward through the nozzle from the pitch box. The pitch is heated to a temperature of about 130 degrees preferably, and is operated under 60 pounds of air pressure, the operation of pitching the keg taking under these conditions about six seconds. As the pitch in the various pitch boxes *j* becomes depleted, as the table revolves the pipes *o* are brought into communication with the outlet *l*, or cut away portion, whereupon the air pressure in the box *j* is relieved and the pitch may flow into the box through the port *l*. In case there should not be a keg upon a cradle when it comes into the operation position, the weighted lever *v* will keep the air pressure cut off, but the roller *w* will serve to co-operate with the keg roller over its surface and

maintaining the air inlet open for operative purposes.

Having described my invention, what I claim and desire to secure by Letters Patent 5 is:—

1. In a pitching machine, the combination of a rotary table, a series of keg supports, pitching means co-operating with the keg supports, means for operating the pitching 10 means, and an automatic safety device in the path of the keg in its movement for controlling the admission of fluid pressure to the respective pitching devices.
2. In a pitching machine, the combination 15 of a movable table, a series of keg supports, pitching means co-operating with the keg supports, a source of fluid pressure, means whereby the source of fluid pressure is brought successively into communication 20 with the respective pitching means, and an automatic safety device in the path of the keg in its movement for controlling the admission of fluid pressure to the respective pitching devices.
3. In a pitching machine, the combination 25 of a movable table, keg supports carried thereby, pitching means traveling with the keg supports substantially as described, and an automatic safety device in the path of the 30 keg in its movement for controlling the admission of fluid pressure to the respective pitching devices.
4. In a pitching machine, the combination 35 of a rotary table, a series of keg supports, a series of pitching devices moving with the said keg supports, and an automatic safety

device in the path of the keg in its movement for controlling the admission of fluid pressure to the respective pitching devices.

5. In a pitching machine, the combination 40 of a series of keg supports, a table supporting the said keg supports, pitching means traveling with the table, and an automatic safety device in the path of the keg in its movement for controlling the admission of fluid pressure 45 to the respective pitching devices.

6. In a pitching machine, the combination 40 of a rotating table, a series of keg supports carried thereby, pitching means also carried by the said table, and an automatic safety 50 device in the path of the keg in its movement for controlling the admission of fluid pressure to the respective pitching devices.

7. In a pitching machine, the combination 55 of a rotary table, a series of keg supports, pitching means and an automatic safety device in the path of the keg in its movement for controlling the admission of fluid pressure to the respective pitching devices.

8. In a pitching machine, the combination 60 of a rotary table having keg supports, pitching means, a source of fluid pressure for effecting the operation of the pitching means and an automatic safety device in the path of the keg in its movement for controlling the ad- 65 mission of fluid pressure to the respective pitching devices.
